UNITED STATES PATENT OFFICE.

EDWARD C. SCHWINGEL, OF BUFFALO, AND RALPH W. TURNER, OF EAST AURORA, NEW YORK.

FAUCET.

SPECIFICATION forming part of Letters Patent No. 789,569, dated May 9, 1905.

Application filed May 17, 1904. Serial No. 208,358.

To all whom it may concern:

Be it known that we, EDWARD C. SCHWINGEL, a resident of Buffalo, and RALPH W. TURNER, a resident of East Aurora, in the 5 county of Erie and State of New York, citizens of the United States, have invented new and useful Improvements in Faucets, of which the following is a specification.

This invention relates more particularly to 10 faucets for metal and wooden shipping casks, barrels, and analogous liquid-containing receptacles.

The objects of the invention are to provide 15 a desirable faucet of simple and inexpensive construction, which can be readily secured in the bung-holes of metal and wooden liquid-containing vessels, which has a movable discharge-tube adapted to project beyond the wall of the vessel when in use and to be moved 20 back into the vessel when not in use, whereby it is protected from injury by contact with nearby objects, which will not leak, and which is so constructed that the discharge-tube can 25 remain in its projected position and the flow of the liquid therefrom be controlled as desired.

In the accompanying drawings, Figure 1 is 30 a fragmentary sectional elevation of a metallic shipping vessel provided with a faucet embodying the invention, showing the discharge-tube in its inner position. Fig. 2 is a similar view showing the discharge tube projected. Fig. 3 is a transverse section of the faucet in line 3 3, Fig. 1. Fig. 4 is a similar section in 35 line 4 4, Fig. 2. Fig. 5 is a front elevation of the faucet, its protecting-cap being removed. Fig. 6 is a fragmentary sectional elevation of a wooden cask provided with the faucet.

Like letters of reference refer to like parts 40 in the several figures.

A represents a hollow sleeve or shell in 45 which the parts of the faucet are contained. The sleeve is preferably of tapering or frusto-conical form and projects into the cask or vessel to which it is secured through the bung-hole or other analogous hole in the wall of the vessel. Fig. 1 shows the faucet applied to the lower portion of the cylindrical wall of a metallic cask or vessel. Such vessels

are ordinarily provided with bung-holes having internally-threaded bushings b, and the shell is provided near its outer end with an external screw-thread c, by which it is screwed into the bushing. This thread is adapted to fit the bushings ordinarily employed, thus enabling the faucet to be applied to casks or vessels now in use. The faucet can be applied either to the cylindrical wall or head of the cask or vessel. As shown in Fig. 6, the faucet is also capable of use with an ordinary 55 wooden cask or barrel, in which case the shell can be screwed directly into the unbushed bung-hole, its screw-thread c, which is sufficiently sharp, cutting a thread for itself in the wood of the vessel. The shell is provided with one or more—preferably two—liquid-discharge openings d and preferably has at its outer end a flange e, which is notched or otherwise fashioned for the application of a wrench or tool for screwing the shell into 60 the hole of the vessel.

F represents a hollow valve or turn-plug, 65 which is preferably of tapering or frusto-conical form, and is rotatably held in the correspondingly-shaped bore of the shell, in which 70 it is secured by the usual key-washer f and adjusting-nut f', screwed on the threaded reduced end of the turn-plug. The latter is provided with one or more, preferably two, liquid-discharge openings G, adapted to be 75 moved into and out of register with the discharge-opening d of the shell by turning the plug. The plug can be turned by hand; but its outer end is preferably of polygonal or other suitable shape for receiving a detachable wrench or handle H for turning it.

I represents a movable discharge-tube arranged to slide longitudinally in the cylindrical bore of the turn-plug. Its inner open 80 end is preferably provided with a flange or shoulder i, which slidably fits in the bore of the turn-plug, while its outer end has a downwardly-directed discharge-nozzle i', which may be formed integrally with the discharge-tube or by a separate fitting secured on the 85 end of a straight tube.

K represents a stuffing-box, which surrounds the discharge-tube at the front portion

of the turn-plug to prevent leakage around the discharge-tube. The stuffing-box may consist of the divided nuts *k*, shown screwed into the internally-threaded outer portion of 5 the turn-plug, with an interposed packing or washer *k'*, or it may be of any other suitable construction. The front end of the turn-plug preferably has a cavity *l* large enough to receive the discharge-nozzle *i* and a ring or 10 handle *l'*, with which the discharge-tube is provided for pulling it out to operative position.

M represents a protecting-cap for inclosing and protecting the outer ends of the turn-plug and discharge-tube. The cap or cover shown 15 has a reduced threaded portion, which screws into an internally-threaded cavity *m* in the flanged outer end of the sleeve or shell A of the faucet. The cap is of polygonal or other shape adapting it to be turned by an ordinary 20 wrench or tool.

When the discharge-tube I is pushed in and the cap or cover M is applied, as shown in Figs. 1 and 6, the parts of the faucet are all 25 inclosed and protected, so that they cannot be injured in handling the vessel to which the faucet is applied and cannot be struck by an object and broken purposely or accidentally. The cap or cover projects from the wall of the vessel only about as far as the usual bung and 30 is not an objection. When the faucet is to be used, the cap or cover is removed and the telescoping discharge-tube I is pulled out, as indicated in Fig. 2. The wrench or handle H, Fig. 2, is then applied to the front end of 35 the turn-plug F and the latter turned to move its discharge-openings into register with those in the shell or sleeve A, thus permitting the contents of the cask or vessel to discharge. The discharge-tube can remain in its projected 40 position, if desired, and the flow of the liquid can be regulated or entirely shut off by turning the valve or turn-plug without disturbing the discharge-tube, its action being the same as that of the well-known turn-plug valve. 45 Should the turn-plug be accidentally turned into discharging position while the discharge-tube is in its inner position, the contents of the vessel cannot escape, because the flange *i* at the inner end of the discharge-tube cuts off 50 communication between the tube and the discharge-openings of the turn-plug.

We claim as our invention—

1. The combination of a faucet-shell which is secured at its outer portion to a vessel and 55 projects into the vessel, a discharge-tube which is movable in said shell into and out of discharging position, a valve movable independently of the discharge-tube to control the flow of liquid, and a protecting-cap which is sepa-

rate from said discharge-tube and is removably secured to said shell and incloses said discharge-tube and said valve, substantially as set forth. 60

2. The combination of a faucet-shell which is secured to a vessel and projects thereinto, a 65 discharge-tube movable in said shell into and out of discharging position, and a valve concentric with said discharge-tube and movable independently of the latter to control the flow of the liquid, substantially as set forth. 70

3. The combination of a faucet-shell which is secured to a vessel and projects thereinto, a discharge-tube movable in said shell into and out of discharging position, and a turn-plug arranged longitudinally of said discharge-tube 75 and movable independently of the latter to control the flow of the liquid, substantially as set forth.

4. The combination of a faucet-shell which is secured to a vessel and projects thereinto, a 80 discharge-tube movable in said shell into and out of discharging position, and a valve surrounding said discharge-tube and movable independently of the latter to control the flow of the liquid, substantially as set forth. 85

5. The combination of a faucet-shell which is secured to a vessel and projects thereinto, a hollow turn-plug rotatable in said shell and having a discharge-opening adapted to register with a discharge-opening in said shell, and 90 a discharge-tube slidable in said turn-plug, substantially as set forth.

6. The combination of a faucet-shell which is secured to a vessel and projects thereinto, a hollow turn-plug rotatable in said shell and 95 having a discharge-opening adapted to register with a discharge-opening in said shell, and a discharge-tube slidable in said turn-plug to establish and cut off communication between itself and said discharge-opening in the turn-plug, substantially as set forth. 100

7. The combination of a faucet-shell which is secured to a vessel and projects thereinto, a hollow turn-plug rotatable in said shell and having a discharge-opening adapted to register with a discharge-opening in said shell, said turn-plug projecting out of said shell, a discharge-tube slidable in said turn-plug, and a removable cap which incloses said turn-plug and discharge-tube, substantially as set forth. 105 110

Witness our hands this 14th day of May, 1904.
